UNITED STATES PATENT OFFICE.

CHARLES S. HILL, OF BOSTON, AND WILLIAM E. BAILEY, OF BEVERLY, MASSACHUSETTS; SAID BAILEY ASSIGNOR TO SAID HILL.

HEEL-NAILING MACHINE.

SPECIFICATION forming part of Letters Patent No. 511,951, dated January 2, 1894.

Application filed May 12, 1891. Serial No. 392,454. (No model.)

To all whom it may concern:

Be it known that we, CHARLES S. HILL, of Boston, and WILLIAM E. BAILEY, of Beverly, Massachusetts, have invented a new and useful Improvement in Methods of and Mechanism for Attaching Heels to Boots, of which the following is a specification.

The invention consists in combinations of mechanism and details of construction, as hereinafter set forth, by which the "finish" nails or slugs in a boot heel are driven simultaneously with the spanking of the top lift.

In carrying out our invention, we have perforated the spanker plate with holes corresponding to the position of said "finish" or other outside nails in the completed boot and provided the nail block with a corresponding set of drivers of sufficient length to pass through the said holes in the spanker plate, at the same time giving to the driver plate a limited horizontal motion in addition to its vertical motion beneath the nail block, and furnishing it with a set of inclined recesses into which the ends of the long drivers for the said "finish" or other outside nails may drop when the driver plate is in position (see Fig. 2) to operate the shorter drivers that the latter may give their blows as previously described to the nails projecting from the heel body. When the driver plate ascends for this last mentioned purpose it carries with it the longer drivers, but since their heads are in the said recesses the said long drivers are not carried up far enough to do any harm.

In the operation of the machine as improved by us when the driver plate ascends to operate the shorter drivers it has been swung a little to one side, its general flat surface permitting it readily to pass under the heads of the short drivers, while the long drivers enter the inclined recesses. We have also given to the spanker plate a vertical motion in addition to the horizontal motion it had in the machine before the improvement was made; and in the further operation of the improved machine after the jack has been raised carrying with it the boot and attached heel body, upon which the top lift is to be blind-nailed, the spanker plate, which thus far has been

raised to its highest position and swung to one side, is now swung back and lowered into contact with the nail block, its perforations coinciding with the perforations in the nail block containing the long drivers. A top lift 55 with the "finish" or other outside nails sticking into it is now placed upon the spanker plate with the heads of the said nails in the said perforations before it is swung back to its last named position. The driver plate is 60 also swung back to its original position under the nail block, thus bringing the heads of the long drivers out of the inclined recesses so that they rest upon the top surface of the driver plate, and the jack with the 65 boot and heel body being now brought over the top lift, the driver plate is caused to ascend with sufficient force to drive the finish or other showing nails home, while by the same movement the top lift is spanked upon 70 the heel body.

In the drawings:—Figure 1 represents a side elevation of a portion of a heelning machine with the improvements attached, showing the jack, the jack holding device, the 75 plunger or driver, and a portion of the frame of the machine. Fig. 2 represents a plan view of the improvements mounted upon the head of the plunger, showing the spanker plate, and its attached top lift clamps raised and turned 80 to one side, to the position occupied while the heel is being attached to the boot, and the top lift is being placed within the top lift clamps. Fig. 3 represents a sectional side elevation (seen from the left in Fig. 2) of 85 the same, showing the spanker plate and top lift clamps turned into position above the nail block and drivers and ready to be drawn down upon the same. Fig. 4 represents a horizontal section of the device, on the line 90 $z z$ shown in Fig. 3, showing the mechanism for adjusting the length of the finish-nail or slug drivers. Fig. 5 represents an opposite side elevation of the device from that shown in Fig. 3, showing the spanker plate resting 95 upon the nail block. Fig. 6 represents a vertical section of the device on the line $y y$ shown in Figs. 4 and 5, showing the various parts in the positions occupied when the top lift is spanked upon the heel and the "finish" 100

nails or slugs are driven. Fig. 7 represents a central vertical section at right angles to that shown in Fig. 6, showing the parts in the same positions as occupied in said Fig. 6.

- 5 A is the frame of the heelng machine.
 J is a sliding jack.
 S is the die bed spindle.
 B is the nail block supported upon a post P dropping into the die bed spindle. A spring (not shown) within the die bed spindle beneath post P tends to keep the nail block elevated above the driver plate D hereinafter to be described.

The nail block B for convenience is made 15 in two parts m and u, but so far as this invention is concerned might be in one piece.

T is the spanker or top lift plate supported by a vertical spindle a, to which it is rigidly attached and which turns in a hole h extending 20 through a projection b from a corner of the nail block. As shown, the projection is actually from the lower portion m of the nail block. If the nail block were made in one piece it would be necessary to cut away the 25 upper portion above the projection b in order to give room for two half collars c and c' hereinafter described. The spindle a has a vertical movement in the said hole h, and this vertical movement with the turning of the 30 spindle a in said hole h gives to the spanker plate T a vertical as well as a horizontal movement with reference to the nail block.

L is a bent lever pivoted to the nail block at p, with the free end of its long arm bearing 35 upon the lower surface of the spanker plate near the spindle a.

L' is a lever pivoted to the nail block at p', one end of which bears upon the short arm of lever L, while the other end is furnished 40 with a thumb-piece as shown. By pressing upward on the said thumb-piece the two levers L' and L are operated to raise the spanker plate from the nail block and with it the spindle a. This spindle a near its top 45 has a rigidly attached half collar c, which when the spindle is raised just clears another half collar c' rigidly attached to the projection b of the nail block. After the spanker plate and spindle are lifted as described the 50 spanker plate may be swung to one side, the collar c resting upon the collar c', as shown in Fig. 2. A spring s attached to a pin p² on the spanker plate and to a pin p³ in the nail block tends to swing the spanker plate to the 55 position shown at Fig. 5. A spring s' within the hole h pressing against a shoulder on spindle d formed by enlarging the diameter of said spindle throughout its lower portion, tends to lower the spindle and the spanker 60 plate.

G is a long cog or gear secured to a sleeve E by a friction washer w and nut or collar c² as shown, the said sleeve E being in turn keyed to spindle a. For additional support

the said sleeve E has a flange at its upper end 65 which rests or bears upon two brackets g and g' pinned to projection b.

D is the driver plate having a vertical, and, by means hereinafter described, a horizontal, movement relatively to the nail block, to 70 which it is secured by post P passing through a hole h² in said driver plate, and post P' which extends upward from a sliding attachment (R) to the die bed spindle, (an adjusting device in the machine proper for different sized heels,) passes through a curved slot t in the driver plate, and finally enters the nail block, as shown; and d, d, d, &c., are the nail drivers whose heads rest on the top of the driver plate, while their other ends penetrate into holes l, l, l, &c., that extend through the nail block.

The driver plate D at one corner is furnished with teeth, as shown, with which the cog G engages at any vertical position of the driver 85 plate; and accordingly the driver plate as well as the spanker plate T, turns with the spindle a, but the movement of the driver plate in either direction is limited by the slot t and post P²; the cog G, during the continued movement of the spanker plate, slipping on the sleeve E. The driver plate has upon its upper surface three inclined recesses t' t' t' into which the heads of three slug drivers d' d' d', or drivers for the "finish" nails, fall when 90 the driver plate is swung to the position for operating the shorter nail drivers d, d, &c. The drivers d' d' d' are in holes l' l' l' in the nail block B. The spanker plate T has three corresponding holes l² l² l² which, when the 95 spanker plate is swung back, as before described, and dropped into position for spanking the top lift upon the nails projecting from the heel body, coincide with the holes l' l' l' in the nail block. At the same time the driver 100 plate is swung back, the three drivers d' d' d' rising from their inclined recesses t' t' t', so that their heads lie upon the flat surface of the driver plate. The heads of the "finish" 105 nails or slugs being now in the holes l² l² l² of the spanker plate may now be driven at the 110 same time that the top lift is spanked upon the nails projecting from the heel body.

We claim as our joint invention—

1. In a heelng machine, the combination 115 with the nail block provided with holes for drivers, and drivers in said holes, of a driver plate having a lateral as well as a vertical movement on one face of said nail block and provided with inclined recesses to receive the 120 heads of a portion of said drivers, and a spanker plate having both a vertical and a lateral movement over the other face of said nail block, and provided with perforations corresponding to the drivers whose heads enter said recesses in said driver plate, substantially as described.
2. In a heelng machine, the combination 125

with the nail block B, furnished with drivers of different lengths, of the recessed driver plate D and perforated spanker plate T, the said spanker plate and driver plate being 5 geared together, substantially as described.

3. In a heeling machine, the combination of the recessed driver plate D and perforated

spanker plate T, geared together, substantially as described.
